UNITED STATES PATENT OFFICE.

JOHN GEORGE ROBINSON, OF MANCHESTER, ENGLAND.

STEAM-SUPERHEATER FOR LOCOMOTIVE AND OTHER BOILERS.

1,109,303.

Specification of Letters Patent. Patented Sept. 1, 1914.

Application filed March 23, 1912. Serial No. 685,857.

To all whom it may concern:

Be it known that I, JOHN GEORGE ROBINSON, a subject of the King of Great Britain and Ireland, residing at Manchester, in the county of Lancaster, England, (whose post office address is "Boothdale," Fairfield, Manchester, in the county of Lancaster, England,) have invented certain new and useful Improvements in and Relating to 10 Steam-Superheaters for Locomotive and other Boilers; and I do hereby declare the following to be a full, clear, and exact description of the invention, such as will enable others skilled in the art to which it 15 appertains to make and use the same.

This invention relates to improvements in steam superheaters, for locomotive and other boilers, of the kind in which the ends of the superheater pipes or elements are secured to a wall of a suitably situated header or steam collector, said wall being provided with holes in which said pipe ends are secured or with which the pipe ends are held in registration.

20 My invention relates more particularly to headers or steam collectors for use, primarily, in connection with steam superheaters of the type wherein the superheater elements or pipes are arranged in the fire-tubes or flues of a boiler so that they will be heated by the gases of combustion, the said pipes being connected to a header divided into compartments, into certain of which compartments the saturated steam 25 enters, and thence flows through the pipes into the other compartments of the header.

The principal object of my invention is to provide an improved construction of header of the above type.

30 In the accompanying drawings:—Figure 1 is an elevation, partly in section, of one form of header according to this invention having seven transverse compartments and arranged for 18 superheater elements or 35 pipes; Fig. 2 is a plan partly in section of the header shown in Fig. 1, and Fig. 3 is a cross section of the header taken on the lines A—B Figs. 1 and 2, looking in the direction of the arrows. The header according to the above figures is such that one side or half of the header feeds the steam pipe to one cylinder valve chest and the other

side or half of the header feeds the steam pipe to the other cylinder valve chest. Figs. 4 and 5 show respectively an elevation and a plan, both partly sectional, of a header having seven transverse compartments and arranged for 18 superheater elements similar to that shown in Figs. 1, 2, and 3 but in which, to balance the header a port is provided in the removable front cover so as to connect the superheated steam compartments at either side of header to one another, so that if for any cause one cylinder at any particular time requires more steam than the other cylinder superheated steam from that side of the header whose cylinder requires the lesser amount of steam may pass to that side of the header whose cylinder requires the greater amount of steam and thus "balance" the steam supply to both cylinders. Fig. 6 is a sectional elevation of the header shown in Figs. 4 and 5, taken on the line C—D Fig. 5 and looking in the direction of the arrow, and Fig. 7 is a sectional elevation of the headers shown in Figs. 1 to 6, taken on the lines E—F Figs. 1, 2, 4 and 5 and looking in the direction of the arrow the removable front covers being omitted.

35 Referring to the drawings, the box or casing which forms the header consists of, or is divided by interior walls or partitions into a number of compartments arranged transversely of the greatest length of the header, the alternate compartments being saturated and superheated steam compartments, compartments 1, 3, 5 and 7 being for superheated steam and compartments 2, 2^a, 4, 6 and 6^a being for saturated steam.

40 8 is a tubular boss at the rear of and communicating with compartment 4, having a flange 9 for connecting the pipe conveying the saturated steam from the steam space of the boiler to the header, and 10, 11 are flanges for connecting to the header at compartments 1 and 7 the steam pipes 12, 13 respectively, conveying the superheated steam from the header to the valve chests of the engine cylinders, 14 being screw-threaded studs or dowels fixedly mounted in the metal of the header and 15 nuts cooperating with said studs or dowels by which studs and nuts said flanges 10, 11 are

secured in position. If desired the metal of the front wall at the places where said flanges 10, 11 are secured may be thicker than at other places, and said thickening 5 may be external (as shown in Figs. 2 and 5) or internal.

Compartments 1, 2, 3, 4, 5, 6 and 7 are formed open at the front, and compartments 2, 3, 4, 5 and 6 are adapted to be closed 10 by a cover plate 16 removably secured or held in position by nuts 17 screwed on to threaded studs or dowels 18 fixedly mounted in metal at the front of the header body or casting. The front faces or edges of the 15 various walls of the header with which said plate or cover 16 contacts may be, and preferably are suitably thickened out or flanged to provide better jointing faces or surfaces. The faces of the front wall with which the 20 cover 16 and flanges 10, 11 contact are machined true and smooth. If desired instead of the cover 16 and flanges 10, 11 actually contacting with the front wall of the header suitable joint making material may be placed 25 between them and said wall, such for instance as copper wire gauze.

22 are lugs which may be provided at the ends of the header and by which it may be secured to suitable brackets in the smoke 30 box, and 24 are strengthening webs of metal that may be provided if thought desirable at suitable places on the header. The ends 35 20, 21 of the superheating pipes or elements are expanded directly into holes drilled or otherwise provided therefor in the bottom wall 25 of the header which thus constitutes a "tube plate." The tube plate 25 forms the bottom or lower wall of all the transverse compartments of the header, and the bottom 40 40 of the compartments being all at the same level the tube plate 25 is thus in effect a flat straight plate.

The several saturated steam compartments of the header are connected to one another 45 by ports or passages 26, 27 in the header. In Figs. 1 to 7 inclusive these ports or passages 26, 27 are arranged in or at the top of the box or casting forming the header and pass over or above the superheated steam 50 compartments 3 and 5 respectively so as to place saturated steam compartments 2 and 6 in communication with compartment 4 and therefore with one another.

The superheater steam compartments 1 55 and 3 are connected to one another by a port or passage 28 and the superheater steam compartments 5 and 7 are connected to one another by a port or passage 29. In the headers shown in Figs. 1 to 7 inclusive 60 the ports or passages 28, 29 are located in or at the back or rear of the box or casting forming the header and behind the saturated steam compartments 2 and 6 respectively. The superheated steam compartments 3 and 65 5 are also connected, or placed in commun-

cation, with one another by means of a port or passage 30 and all the superheated steam compartments are thereby connected or placed in communication. In the header shown in Figs. 4 to 7 the said port or passage 70 30 is located in the removable front cover 16 and thus passes in front of saturated steam compartment 4.

The open ends of the port or passage 30 formed or provided in the removable front 75 cover 16 of the header come opposite or register with the openings at the front of superheated steam compartments 3 and 5 when the said cover 16 is placed in position, and the back wall or bridge piece 31 of the passage 80 30 in the cover comes in front of and closes the opening at the front of saturated steam compartment 4.

It will further be seen that the ends of the 85 superheater elements or pipes can, with a header according to this invention, be readily expanded in their holes in the tube plate of the header by means of a suitable tool inserted through the openings of the several compartments after the front cover plate 16 90 has been removed. The superheater elements or pipes can also be readily driven out by a suitable tool or appliance inserted through such openings, the form and dimensions of the said compartments being suitable 95 for these purposes.

What I claim as my invention and desire to secure by Letters Patent is:—

1. In a superheater, the combination, with superheater elements; of a header provided 100 with integrally-formed transverse and longitudinal partitions which divide it into compartments and longitudinal steam passages, said compartments comprising chambers for saturated steam and chambers for superheated steam arranged alternately and side by side, one of the said passages being arranged at the top of the header and connecting the chambers of one series, and the other passages being arranged at the back of the 110 header and connecting the chambers of the other series, and all the chambers having hand-openings at their front sides and having the superheater elements connected to their bottom sides; and removable covering 115 means for closing the said hand-openings.

2. In a superheater, the combination, with superheater elements; of a header provided with integrally-formed transverse and longitudinal steam passages, said compartments 120 comprising chambers for saturated steam and chambers for superheated steam arranged alternately and side by side, one of the said passages being arranged at the top of the header and connecting the chambers 125 of one series, and the other passages being arranged at the back of the header and connecting the chambers of the other series, and all the chambers having hand-openings at their front sides and having the superheater 130.

elements connected to their bottom sides; and removable covering means for closing the said hand-openings, said covering means being provided with a longitudinal steam 5 passage which forms a supplementary communication between certain of the similar steam chambers of one series.

In testimony whereof I affix my signature, in presence of two witnesses.

JOHN GEORGE ROBINSON.
